UNITED STATES PATENT OFFICE.

CHARLES W. SIEMENS, OF WESTMINSTER, COUNTY OF MIDDLESEX, ENGLAND.

ROTATIVE REGENERATIVE FURNACE.

SPECIFICATION forming part of Letters Patent No. 244,492, dated July 19, 1881.

Application filed December 9, 1879.

To all whom it may concern:

Be it known that I, CHARLES W. SIEMENS, of Westminster, county of Middlesex, England, have invented an Improvement in Rotative 5 Regenerative Furnaces.

The following description, taken in connection with the accompanying plate of drawings, hereinafter referred to, forms a full and exact specification, wherein are set forth the nature 10 and principles of the invention, by which the same may be distinguished from others of a similar class, together with such parts thereof as are claimed as new and are desired to be secured by Letters Patent of the United States.

For many years three classes of rotary machines for puddling and melting iron have been known. In one class of machines of this character a cylindrical or partially spherical vessel is rotated on a horizontal axis; in another 20 class a basin is made to revolve in a horizontal plane, and in still another class the sole or hearth of the furnace revolves on an inclined axis. The English patent of Maudsly, No. 1,436, dated June 5, 1858, the subject-matter 25 of which is now public property in this country, shows a furnace constructed in such a manner that motive power may be imparted to the bed thereof for the purpose of causing it to rotate in either a horizontal or inclined plane. Al- 30 though the bed of the furnace described in said English patent may be made to revolve in a horizontal plane, the axis of revolution is placed, by preference, about ten degrees out of the perpendicular, so that one side of the bed 35 will be lower than the other. The furnace de- 40 scribed in said English patent has also a lower frame supplied with wheels, by means of which the revolving bed may be withdrawn from beneath the cover of the furnace.

Attempts have been made to improve the construction of regenerative furnaces constructed on the Siemens system by applying thereto rotative and removable hearths. Thus, in the United States patent of Charles Pernot, No. 45 169,033, dated October 19, 1875, a converting-furnace having a system of regenerators and flues arranged as described in United States patent to C. W. Siemens is provided with an inclined and removable hearth. In this fur- 50 nace the gas and air enter at one end of the hearth and the products of combustion pass

off at the opposite end. (See, also, the patent of August Ponsard, in which substantially similar modifications of the Siemens furnace are shown.)

In the accompanying plates of drawings, in which corresponding parts are designated by the same letters, Figure 1 is a longitudinal vertical section of a furnace having a fixed chamber with a revolving bottom or pan, taken 55 on the line A' B', Fig. 2. Fig. 2 denotes a transverse vertical section of the same, taken on the line C' D' of Fig. 1. Fig. 3 is a longitudinal vertical section of a furnace having an inclined fixed chamber with a bottom or pan capable 60 of revolving in an inclined plane taken at the line A'' B'' of Fig. 4. Fig. 4 is a transverse vertical section of the same, taken at the line C'' D'' of Fig. 3.

In these furnaces the air-regenerators are ar- 70 ranged to communicate with one and the same side of the furnace, and the furnace-bed is thereby rendered accessible on all the other sides. Air only passes through the reversible regenerators to the furnace, and gas enters the 75 chamber in a continuous manner from the source of supply through the gas-inlet, which is situated below and between the air and combustion-product passages. The gas-inlet is of 80 such a width and so arranged with reference to the passages communicating with the regenerative chambers that the gas from the generator is caused to expand laterally beneath the air-currents.

The gas-producers' reversing and regulating 85 valves are not shown in the drawings, as they are of my usual well-known construction, and therefore need no description.

The gas produced rises from the producers continuously and flows out through the regulating slide-valves into the gas-flue, along which it passes through the port B to the chamber A of the furnace. Thus, gaseous fuel flows continuously through port B, while the lateral ports C serve alternately to give ingress to 90 the hot air and egress to the products of combustion, as described in United States Letters Patent granted to me March 12, 1878, for a furnace revolving upon a horizontal axis.

The door or working-hole L opens directly 100 upon the revolving basin D, and is situated diametrically opposite to the side of the basin

or revolving hearth at which the gas and air enter, and the products of combustion leave the combustion-chamber. The revolving basin is located within a transverse passage extending entirely under the combustion-chamber, and mounted upon a car, E, in such a manner as to be capable of revolution in a horizontal plane or about a vertical or inclined axis. The said car is provided with wheels e, which run upon the track F, and may be readily withdrawn when it is desired to remove the revolving basin from its position beneath the combustion-chamber.

The basin may be rotated by many mechanical appliances now in use, which will readily suggest themselves to a practical mechanic, and may be operated by any suitable motor adapted to impart continuous rotary motion or motion capable of being increased or diminished at will. I have found the mechanical combination illustrated in the drawings a good one for these purposes.

The axis upon which the basin is mounted is guided by a proper bearing, n, and the rollers o, upon which the basin runs, travel upon a circular track, m, which forms a part of the car E. Continuous rotary motion is imparted to the basin by means of a worm-wheel, which is operated by the tangent-screw Y. The rotary motion thus imparted may be rendered

variable or intermittent by the use of a proper motor. When the plane of rotation is inclined or at an angle with the plane of the horizon the construction of the car and circular track will be modified accordingly. When the rotating hearth or basin revolves about an inclined axis the flue communicating with the gas-supply is inclined from the horizontal, as are also the air and combustion-product passages, in order that the gas and air may be mixed upon the most favorable conditions and complete combustion effected.

I claim and desire to secure by Letters Patent of the United States—

1. A regenerative furnace having a removable revolving hearth, inclined top, and downwardly-inclined gas-passage, through which the gas enters continuously from the source of supply. 45

2. A regenerative furnace having a revolving hearth, an inclined top or crown, and a gas-inlet located below and between the air and combustion-product passages. 50

In testimony that I claim the foregoing I have hereunto set my hand and seal this 24th 55 day of November, 1879.

C. WILLIAM SIEMENS. [L. S.]
